UNITED STATES PATENT OFFICE.

WILLIAM H. McWHIRTER, OF PONTOTOC, MISSISSIPPI.

FENCE-POST.

No. 913,907.

Specification of Letters Patent.

Patented March 2, 1909.

Application filed February 26, 1908. Serial No. 417,985.

To all whom it may concern:

Be it known that I, WILLIAM H. McWHIRTER, a citizen of the United States, residing at Pontotoc, in the county of Pontotoc and State of Mississippi, have invented certain new and useful Improvements in Fence-Posts, of which the following is a specification.

My invention has relation to fences, and more especially to the posts thereof; and the object of the same is to provide an improved post that will hold one or more fence wires, or a web wire fence securely and rigidly.

With this end in view, my post is made of cast-iron or cast-steel parts as are more fully set forth in the following specification and specifically pointed out in the claims hereunto appended.

Referring to the drawings, which form a part of this specification, and which are for illustrative purposes only, and are therefore not drawn to scale:—Figure 1 is the side elevation of a fence, showing in connection therewith my improved fence post, having lower parts of the clencher-bar broken away to show the construction thereof. Fig. 2 is a side elevation of my invention in which the clencher-bar is pressed down in position. Fig. 3 is a top view of my post, showing how the clencher is held in place. Fig. 4 is a side elevation of the post, the clencher-bar removed, showing the manner in which the notches are cut in said post. Fig. 5 is a rear elevation of the clencher-bar, showing to each notch cut therein, there is a corresponding notch cut in the post. Fig. 6 is a front elevation of my invention, the clencher-bar removed. Fig. 7 is a cross-sectional view of my improved post on the line 7, 7 of Fig. 1. Fig. 8 is a vertical sectional view of the post, showing the manner in which the wire is securely clenched into place. Fig. 9 is a cross-sectional view of the post, the clencher-bar removed.

Referring more particularly to the drawings, the post 1, is securely held in the ground by the base 2, which tapers down to a point, but is of uniform thickness. Formed to the front side, and running vertically from the shelf 3, and nearly to the hole 4, is a notched rib 5, said shelf being provided with two holes 6, through each of which pass one of two downwardly extending projections 7, of the clencher-bar 8, one of the said projections formed on each of the side members 9,

of said clencher-bar. Secured to or formed on the upper portion of said post are supports 10, having notches cut in their rear part for the reception of the cross-piece 11, secured in recesses cut in the upper rear corners of said side members of said clencher-bar. Cut in the rear edges of said side members of said clencher-bar are notches 12, which correspond to the notches 13, cut in the front edge of said rib of said post. Passing through the upper end of said post are said hole 4, and the hole 14, being for the reception of the bar 15, which is for the purpose of pressing said downwardly extending projections into said holes in said shelf, after the wires 16, have been pressed through said notches in said rib of said post, and their corresponding notches in said side members of said clencher-bar. After the wire is clenched, forming a loop 17, (which takes up any slack that might exist in the wire, and which clamps it in place securely) and said cross-piece of said clencher-bar is received by said notcher cut in said supports of said post, the bolt, nail or screw 18, (Fig. 3) is passed through said hole 4, for the purpose of holding said clencher-bar in position. It is not absolutely necessary to have the notches in said rib of said post to correspond to notches in said clencher-bar, as said notches in said rib may correspond to the central points of the scalloped portion 19, of said side members. This feature is shown by the notches 20, of said rib, which correspond to the central points of their said respective scalloped portions of said side members of said clencher-bar.

Though I have specifically described my invention I claim the right to make such alterations and changes as will fall within the scope and spirit of my invention and which will be obviously necessary in its manufacture.

What I claim is:—

1. In a device of the character described, the combination of a post having a longitudinal rib secured thereto, said rib having notches cut in its front edge from end to end, a shelf having perforations therethrough, secured to the lower part of said post, a tapering base formed on the lower part of said post, supports formed on said post near its upper end, said supports having notches cut in their rear edges at their tops, a clencher-bar constructed to coact with said post to hold wires in place, and means for holding

said clencher-bar in position, substantially as shown and described and for the purposes set forth.

2. In a device of the character described, 5 the combination of a post having a longitudinal rib secured thereto, said rib having notches cut in its front edge from end to end, a shelf having vertical perforations therethrough, secured to the lower part of said 10 post, a tapering base formed on the lower part of said post for holding the same securely in the ground, supports formed on said post near its upper end, and having notches cut in their rear edges at their tops, a 15 clencher-bar, longitudinal side members having notches cut in their rear edges secured thereto, downwardly extending projections formed on said side members at their lower ends, a cross-piece at the upper ends of said 20 side members, secured in recesses cut in the rear edge at the top ends of the same, and means for holding said clencher-bar in position.
3. In a device of the character described, 25 the combination of a post, a longitudinal rib secured thereto, said rib having notches cut in its front edge from end to end, a shelf having perforations therethrough secured near one end of said post, a base formed on 30 the lower part of said post, supports formed

on said post near its outer end, and having notches cut in their upper edges, a clencher-bar, longitudinal side members having notches cut in their rear edges secured thereto, downwardly extending projections formed 35 on said members at one of their ends, a cross-piece at the other ends of said side members secured thereto, and means for holding said clencher-bar in position.

4. In a device of the character described, 40 the combination of a post consisting of a main body having a rib secured thereto and further provided with a shelf at the lower part thereof, with a clencher-bar so constructed as to adapt itself to said post, said 45 clencher-bar having longitudinal side members having notches cut in their rear edges secured thereto, downwardly extending projections formed on said side members at their lower ends, a cross piece at the upper ends of 50 said side members being secured in recesses cut in the rear edges at the top ends of the same, and means for holding the clencher-bar in position, substantially as shown.

In testimony whereof I affix my signature 55 in presence of two witnesses.

WILLIAM H. McWHIRTER.
